KNIFE SHARPENER

Daniel L. Marcantonio, Westport, Conn., assignor
to The Rayflex Company, Incorporated, Bridge-
port, Conn., a corporation of Connecticut

Application December 13, 1947, Serial No. 791,579

6 Claims. (Cl. 76—87)

1

This invention relates to a knife sharpener, particularly of the type in which there are two or more overlapping hard steel discs across which the edge of the blade is drawn in the sharpening operation, and has for an object to provide an improved and very simple construction which will be very effective in operation and which may be manufactured at low cost.

Another object is to provide a device of this character which may be molded of suitable plastic or similar material, and a further object is to provide a construction in which the sharpener discs may be mounted separately and in which at any time one or more of these discs may be removed and a new one inserted independently of the other discs.

With the foregoing and other objects in view, I have devised the construction illustrated in the accompanying drawing forming a part of this specification. It is, however, to be understood the invention is not limited to the specific details of construction and arrangement shown, but may embody various changes and modifications within the scope of the invention.

In this drawing:

Fig. 1 is a top plan view of the device;

Fig. 2 is a side elevation with parts broken away to more clearly show the construction;

Fig. 3 is a bottom view partly broken away to more clearly show the construction, and

Figs. 4 and 5 are transverse sections substantially on lines 4—4 and 5—5 respectively of Fig. 2.

The device illustrated comprises a body or housing 10 preferably molded of some suitable plastic material in which is mounted a plurality of hard steel sharpening discs 11 and 12. The body 10 includes an upright portion 13 provided with laterally spaced upright side walls 14 and 15, and adjacent one end is provided with a transverse recess or channel 16 extending downwardly from the top wall and opening through the lateral side walls 14 and 15, and preferably curved at the opposite sides of the entrance, as indicated at 17, to facilitate and guide entrance of the knife to the sharpening position. Between this recess and the opposite end of the body the upright side walls 14 and 15 are provided with upright alternate curved ribs 18 and channels 19 forming a finger grip for the device to hold it stationary during the sharpening operation, particularly if the device is not fastened to some support. However, the body is provided on its opposite lower edges with outwardly extending flanges 20 to give a more extended supporting base and also to provide means whereby the device may be

2

mounted on a table or other suitable support by any suitable means, such, for example, as screws (not shown) passing through suitable openings 21 in these flanges.

The body member is molded hollow with a chamber 22 opening through the bottom of the body, which makes it of lighter weight and requires less material, and the body is also provided with a plurality of narrow laterally spaced upright pockets 23 and 24 extending longitudinally of the body, or that is transversely to the recess 16, these pockets being located on opposite sides of the recess 16 and opening through the side walls of this recess. These pockets also extend through the lower side of the body for insertion of the steel sharpener discs 11 and 12. These discs are of the usual form, which are ordinarily circular, flat, very hard steel discs with sharp side edges, and the pockets 23 and 24 are so located that when the discs are in the pocket they project at one edge into the recess 16 with adjacent discs 11 and 12 overlapped at their edges in this recess, as shown in Figs. 1 and 2, to provide the usual V-shaped notch or space 25 between them for the edge of a knife blade when it is drawn across these discs during the sharpening operation. One or more discs may be employed as found desirable, and the discs when assembled in the body are laterally spaced and separated by the dividing walls 26 of the molded material between the respective pockets 23 or 24 in which the discs are mounted.

The chamber 22 within the body is somewhat narrower under the pockets 23 and 24, as indicated at 27, and in the side walls of this narrowed portion there are formed longitudinal channels 28 in which is mounted a gate or closure strip 29. This may be a strip of metal of suitable gauge or thickness guided at its opposite edges in the channels 28 for longitudinal sliding movement to and from a position over the entrances to the pockets 23 and 24 and under the lower edges of the sharpener discs 11 and 12, as indicated in Figs. 2 and 4, to retain these discs in the pockets. It may be retracted to the left or dotted line position, as shown in dotted lines in Figs. 2 and 3, to uncover the discs and permit ready removal or insertion of the discs in the pockets, and to facilitate this operation the free end may be bent downwardly, as indicated at 30, and provided with an opening 31. Also to facilitate insertion of the retainer or closure 29 the side walls of the chamber 22 in the body may be brought up even with the lower edges of the channels 28 at their entrances to form a shoul-

der 32 at the entrances to these channels and another shoulder 33 at its opposite end to support the free end of the closure slide 29.

In manufacture, the body member is molded in one piece of a suitable plastic material with the recess 16 and the pockets 23, 24 molded in it, these pockets being preferably separated by the division walls 26 also molded in one piece with the body, to form separating means between the discs, although if found desirable the pockets could be molded as a single pocket and the discs separated by spacing discs or washers.

In assembling the device, the body is merely placed in an inverted position and the individual sharpening discs 11 and 12 dropped into the pockets 23 and 24 from the lower side. They automatically seat themselves on the tops of these pockets and are properly spaced by the division or spacing walls 26. They are also automatically placed with the side edge of each disc projecting into the recess 16 and overlapping the edge of an adjacent disc projecting into the recess from the opposite side of this recess. Then after the discs have been placed in the pockets the slide or closure 29 is slid to the right as viewed in Figs. 2 and 3 with its edges in the grooves 28 to a position under the lower edges of the discs 11 and 12, as shown in full lines Fig. 2, to thus retain these discs in the pockets. It will be seen that this is a very simple assembling operation, and with this arrangement it is not necessary to connect the discs together. They are each individually dropped into their respective pockets which automatically locates them in proper position and then the slide or closure 29 slid into its normal holding position. If for any reason it is desired to remove one or more discs or to replace them, all that is necessary is to slide the closure 29 to the left, as indicated in dotted lines, Figs. 2 and 3, to release the discs. To facilitate insertion of the slide 29 during the assembling operation after the discs have been placed in their respective pockets, the shoulder 32 is located at the entrances to the guide grooves 28 and on a level with the top walls of these grooves, so that all that is necessary is to merely place the free end of the slide 29 on this shoulder 32 and slide it into the channels or grooves 28, this shoulder 32 guiding it into these channels. In use, the alternate curved ribs and grooves 18 and 19 form effective seats for the fingers of the operator and provide a very comfortable and effective grip for holding the device stationary in the operation of sharpening a knife in the event the device is not fastened to some support.

Having thus set forth the nature of my invention, I claim:

1. A knife sharpener comprising an integral body provided with a transverse recess extending through its top and side walls, said body being provided with a plurality of narrow laterally spaced pockets opening into said recess from the opposite sides thereof and formed in the material of the body so that the side walls of the pockets are formed integral with the body and of the same material as the body, said pockets also opening through the bottom of the body to form entrance openings to permit insertion of separate sharpener discs into said pockets from the bottom of the body, separate unmounted sharpener discs located one in each of said pockets and extending at one edge into the recess in overlapped relation with discs on the opposite side of the recess, the side walls of the pockets also forming the lateral supporting and positioning

means for the discs, and retaining means located over the lower entrance to the pockets to retain the discs in these pockets.

2. A knife sharpener comprising an elongated body member provided with a transverse recess extending through its top and side walls, said body being provided with upright laterally spaced pockets on the opposite sides of said recess and opening into said recess, said pockets being formed in the material of the body so that they are separated by thin division walls integral with the body and of the same material as the body, said pockets being also open at the lower side of the body for insertion of sharpener discs in said pockets, separate unmounted sharpener discs located one in each of said pockets and each extending at one edge into the recess in overlapped relation with a disc extending into the recess from the opposite side thereof, the side walls of the pockets also forming the lateral support and positioning means for the discs, and means over the open lower sides of the pockets retaining the discs in the pockets.

3. A knife sharpener comprising an integral elongated body member provided with a transverse recess opening through its top and side walls, said body also provided with a plurality of laterally spaced upright narrow pockets on the opposite sides of the recess and opening through the sides of said recess, thin division walls integral with the body separating said pockets, and said pockets being also open at the lower side of the body for the insertion of sharpener discs into said pockets, separate unmounted sharpener discs located one in each pocket and each extending at one edge into the recess in overlapped relation with a disc extending into the recess from its opposite side, and retaining means over the open lower sides of the pockets retaining the discs in the pockets.

4. A knife sharpener comprising an elongated integral body member provided with a transverse recess opening through its top and side walls, said body being provided with upright pockets on the opposite sides of said recess and opening into said recess, said pockets being also open at the lower side of the body for insertion of sharpener discs in said pockets and having side walls integral with the body, separate sharpener discs located in said pockets and each extending at one edge into the recess in overlapped relation with a disc extending into the recess from the opposite side thereof, guide means in the lower part of the body, and a slide slidably in said guide means to a position over the entrances to said pockets to retain the discs therein.

5. A knife sharpener comprising an integral elongated body provided with a transverse recess opening through its top and side walls, said body being provided with upright pockets on the opposite sides of said recess and opening into said recess, said pockets being also open at the lower side of the body for insertion of sharpener discs in said pockets, sharpener discs located one in each of said pockets and each extending at one edge into the recess in overlapped relation with a disc extending into the recess from the opposite side of the recess, the body being provided with longitudinal guide grooves in the lower part thereof below and on opposite sides of the entrances to said pockets, a slide plate guided at its opposite edges in said grooves and shiftable to a position over the entrances to said pockets to retain the discs in the pockets, and a shoulder 75 at the entrances to said grooves and on a level

with the upper edge of the grooves to guide the free end of the slide plate into said grooves.

6. A knife sharpener comprising an integral body provided with a transverse recess opening through its top wall and also opening through the sides of the body, said body being provided with at least one upright narrow pocket opening into said recess from each side thereof and also opening through the bottom of the body to form an entrance to the pocket to permit the insertion of a loose unmounted sharpener disc into said pocket, a sharpener disc located in each pocket and extending at one edge into the recess where it is exposed for sharpening a knife blade, the sides of the pocket being integral with the body and forming sole means holding the disc in upright position, and retaining means located

over the entrance to the pocket retaining the disc in the pocket.
